UNITED STATES PATENT OFFICE.

WILLIAM A. TAYLOR, OF PORTLAND, MAINE.

DESIGN FOR A BIRD-SCARER.

SPECIFICATION forming part of Design No. 26,419, dated December 15, 1896.

Application filed October 16, 1896. Serial No. 609,155. Term of patent 7 years.

To all whom it may concern:

Be it known that I, WILLIAM A. TAYLOR, a citizen of the United States of America, residing at Portland, in the county of Cumberland and State of Maine, have invented and produced a new and original Design for Bird-Scarers; and I do hereby declare the following to be a full, clear, and exact description of the invention, such as will enable others skilled in the art to which it appertains to make and use the same.

My invention relates to a new and improved design for bird-scarers, and is so constructed and designed as to be placed on the cornices 15 under the eaves, on the caps of columns of buildings, or suspended among foliage, so as to serve as a means for frightening away birds of all sorts.

In the drawings herewith accompanying and forming a part of this application, Figure 1 is a perspective view of my design. Fig. 2 is a section taken on the line X X in Fig. 1. Fig. 3 is a section taken on the line Z Z in Fig. 1, and Fig. 4 is a section taken on lines 25 Y Y in Fig. 1.

Same letters refer to like parts.

Said drawings represent a nondescript animal having its head and fore shoulders resembling those of a mink, a long body gradually increasing in girth to the hind quarter, as shown at I, and a hind quarter round and of greater diameter than the rest of the body. The animal has erect and prominent ears A,

protruding and staring eyes B, and a long tapering snout C. Extending from either side 35 of the snout are bright, long, and stiff whiskers D. The neck of the animal is very thick and crowning, as shown in Fig. 2 at E. The legs F are straight and project downwardly directly from the shoulder without any knee- 40 joints. In place of feet are round knobs G. The animal is in a sitting position with its legs spread somewhat apart at the bottom, so as to give it greater stability. The hind quarter J of the animal is thick without much regularity of form, and it has no hind legs. It 45 has a short, stubby, and erect tail H.

The color of the device may be varied. It is my practice to give the device a color as nearly as possible resembling the color of the 50 building on which it is used. This I find effects in no way the effectiveness of the device as a scare, but at the same time makes it less liable to be seen from the street by persons passing by.

Having thus described my invention and its use, I claim—

The design for a bird-scarer substantially as herein shown and described.

In testimony whereof I affix my signature, 60 in presence of two witnesses, this 14th day of October, A. D. 1896.

WILLIAM A. TAYLOR.
